UNITED STATES PATENT OFFICE

169,262

AUTOMOBILE BODY

Henry T. King, Detroit, Mich., assignor to Chrysler Corporation, Highland Park, Mich., a corporation of Delaware

Application October 17, 1951, Serial No. 16,990

Term of patent 7 years

(Cl. D14—3)

To all whom it may concern:

Be it known that I, Henry T. King, a citizen of the United States, residing in the city of Detroit, county of Wayne and State of Michigan, have invented a new, original, and ornamental Design for an Automobile Body, of which the following is a specification, reference being had to the accompanying drawings, forming part thereof, in which:

Fig. 1 is a side elevation of an automobile body showing my novel design;

Fig. 2 is a three-quarter rear view in perspective thereof;

Fig. 3 is a rear elevation thereof; and

Fig. 4 is a section taken on line 4—4 of Fig. 1.

The characteristic features of my design are shown in full lines in the drawing.

I claim:

The ornamental design for an automobile body, substantially as shown and described.

HENRY T. KING.
